UNITED STATES PATENT OFFICE.

ROBERT LORENZ, OF NEW YORK, N. Y.

CLAMP FOR STRINGS, &c.

SPECIFICATION forming part of Letters Patent No. 334,711, dated January 19, 1886.
Application filed August 13, 1885. Serial No. 171,260. (No model.)

To all whom it may concern:

Be it known that I, ROBERT LORENZ, of the city, county, and State of New York, have invented certain new and useful Improvements 5 in Clamps for Strings, &c., of which the following is a specification.

This invention has reference to an improved clamp for strings, cords, and ropes; and it consists of a socket-piece having two longitudinal perforations, through which the string is passed in opposite directions, the end of the string being retained in one of the holes by a suitable key.

In the accompanying drawings, Figure 1 represents a vertical longitudinal section of my improved clamp for strings, &c. Fig. 2 is a vertical transverse section on line *x x*, Fig. 1. Figs. 3, 4, and 5 are respectively a front view, a front view with the cover detached, 20 and a vertical transverse section on line *y y*, Fig. 4, of a modified form of my clamp.

Similar letters of reference indicate corresponding parts.

Referring to the drawings, A represents a 25 socket-piece of any suitable metal, which is provided with two longitudinal holes, *a a*, that are arranged parallel to or converging toward each other. The string, cord, or rope B is passed first through one hole *a*, and then over 30 the end of the socket-piece A and back in opposite direction through the second hole *a*. The end of the string B is secured to the first hole *a* by a wedge-key, *b*, whereby the rigid clamping of the string is obtained.

35 A more ornamental form of the clamp is shown in Figs. 3, 4, and 5, in which the fastening-key is arranged in a chamber, *e*, of the socket-piece A, which recess is closed by the detachable cover A'. The end of the string 40 B is attached by a wedge-key, *b*, in said cham-

ber to the socket-piece A, as shown in Figs. 4 and 5. The string B is passed through holes at one end of the socket-piece A and through a guide-hole at the opposite end of the same, as shown in Fig. 4.

Having thus described my invention, I claim as new and desire to secure by Letters Patent—

1. The combination, in a cord-clamping device, of a stock provided with two perforations side by side and a longitudinal web or partition between said perforations, whereby the cord is adapted to be passed through one of said perforations over the intermediate web at one end thereof opposite adjacent ends of both perforations, and returned through the other perforation, and a wedge-shaped pin adapted to work against said cord in one of said perforations at the opposite end thereof, substantially as described.

2. The combination, in a cord-clamping device, of a stock having a chamber and provided with two perforations for receiving the cord, and a wedge-shaped locking-pin inserted in one of said perforations through said chamber, substantially as described. 6

3. The combination, in a cord-clamping device, of a stock having a chamber and a sliding cover therefor, and provided with two perforations for receiving the cord, and a wedge-shaped locking-pin inserted in one of 70 said perforations through said chamber, substantially as described.

In testimony that I claim the foregoing as my invention I have signed my name in presence of two subscribing witnesses.

ROBERT LORENZ.
